Attorney

UNITED STATES PATENT OFFICE

JOHN H. HYDE, OF MARCUS HOOK, PENNSYLVANIA

SPARK PLUG

Application filed February 24, 1932. Serial No. 594,763.

This invention relates to improvements in spark plugs, and an object thereof is to provide a novel, inexpensive and efficient construction whereby atmospheric air may be permitted to enter the hollow interior thereof which is designed to open into a gas engine combustion chamber, for the purpose of supplying air to the engine fuel, and for the purpose of keeping the interior of the plug and the electrodes thereof clean.

Another object of the invention is to provide an advantageous means for opening and closing the atmospheric air passage which leads from exterior to the interior of the plug.

The invention resides in the novel construction, combination and arrangement of elements hereinafter described and claimed.

In the accompanying drawing, illustrating the invention,

Figure 1 is a longitudinal section of a spark plug embodying my invention.

Figures 2 and 3 are transverse sections thereof, on lines 2-2 and 3-3, respectively, of Fig. 1.

Referring to the drawing, the body member 4 of the spark plug is provided with the usual threaded end portion 5 to be screwed into the frame of an internal combustion engine.

The body member 4 is provided with a lower or inner bore 6 having an open end which communicates with the combustion chamber of the engine to which the plug is applied; and the member 4 is provided with an upper or outer bore 7 co-axial with the inner bore 6 and of larger diameter. A shoulder or packing seat 8 is formed at the junction of the inner and outer bores.

The wall of the outer portion of the outer bore 7 is threaded for the reception of a clamping sleeve or collar 9 which is screwed into the same.

Extending centrally through the bores 6 and 7 and the clamping sleeve 9 is an insulating core 10 formed of porcelain or other suitable material and having a centrally arranged expanded portion 11 within the outer bore 7.

The diameter of the expanded portion 11 is almost equal to the diameter of the bore 7,

and the portion 11 is adapted to be clamped between the collar 9 and seat 8. The outer portion of the core 10 extends through the sleeve 9 in spaced relation thereto, and the inner portion of the core 10 extends through the inner bore 6 in spaced relation to the wall thereof.

Fitted to and resting against the seat 8 is a hard metal ring 12, and interposed between the ring 12 and the expanded portion 11 of the core 10 is a packing ring 13 formed of copper or other suitable material which is softer than the hard metal ring 12 to afford a cushion seat for the porcelain forming the portion 11 of the core 10. There is another packing ring 14 interposed between the outer end of the portion 11 and the sleeve 9, and the ring 14 is formed of the same or similar material as that forming the ring 12. The rings 12, 13 and 14 and the expanded portion 11 of the core 10 are clamped by and between the sleeve 9 and seat 8 to hold the core 10 firmly in place within the body member.

The body member 4 is provided with the outer electrode 15, and extending centrally through the core 10 is the inner electrode 16 having a free end portion projecting from the core 10 adjacent to the electrode 15 for the formation of the spark gap 17 between them.

The central portion of the body member 4 is expanded and is hexagonal in shape to receive a wrench for turning the plug, and extending diagonally through the expanded portion 18 of the member 4 is a passage 19 which leads from the exterior of the body member 4 to the interior thereof and communicates with the space between the wall of the bore 6 and the portion of the core 10 which extends through the same. This passage 19 is formed by an outer bore 20 and an inner bore 21 of larger diameter than the outer bore, providing a valve seat 22 at the junction of the two bores. Within the bore 21 and resting normally in contact with the valve seat 22 is a ball valve 23 which is adapted to be raised from the seat 22 by air being sucked through the passage 19. The bore 22 is opposite to one side of the ring 12 which forms a stop or abutment for the ball valve 23 when it is raised or moved inwardly from its

seat. Thus the hard metal of the ring 12 serves to protect the softer material of the packing ring 13 from the impacts of the ball valve.

5 The body member 4 below the expanded portion 18 thereof is provided with an annular groove 24, and slidably fitted within this groove 24 is a spring clip 25 which embraces the member 4 and is circumferentially adjustable thereon within the groove 24. The clip 25 is provided with a spring arm 26 which extends to a position near the outer end of the passage 19 when the clip is in the operative position, illustrated in the drawing. 10 The spring arm 26 has a protuberance 27 thereon which is adapted to enter the passage 19 and engage the wall of the outer end portion thereof and close the same when the clip is in the operative position. By sliding 15 the clip 25 circumferentially within the groove 24 it may be moved from its operative position to move the arm 26 and its protuberance 27 from the passage 19 to open the lower or outer end thereof. Thus the clip 25 may 20 be adjusted at will to open or close the outer end of the passage 19.

When the spark plug is applied to a gas engine, the space between the core 10 and the wall of the bore 6 will be in communication 30 with the combustion chamber of the engine; and, it will now be understood that when the plug is applied to an engine and the clip 25 is set in its inoperative position opening the outer end of the passage 19, the suction created 35 within the combustion chamber of the engine, at each intake stroke of the piston, will open the ball valve 23 and draw atmospheric air into the combustion chamber and mix it with the fuel therein, supplementing 40 the air introduced through the carburetor, and that the atmospheric air thus drawn through the passage 19 and between the core 10 and the wall of the bore 6 and through the 45 spark gap 17 will tend to keep the interior of the plug clean and prevent the fouling thereof. It will also be understood that at each compression stroke of the piston, the ball valve 23 will be forced against its seat 22 and 50 prevent the escape of fuel gas from the combustion chamber through the passage 19.

When atmospheric or other conditions

make it desirable that no atmospheric air shall be admitted to the combustion chamber through the passage 19, the spring clip 25 may be adjusted to its operative position, as shown in the drawing, to close the outer end 70 of the passage 19.

I claim as my invention:

1. A hollow spark plug body member having a passage therein extending from the exterior to the interior thereof and having an exterior, annular groove, in combination with a part slidably fitted to said groove and circumferentially adjustable therein and provided with a yieldable arm projecting therefrom and adapted to engage said member, said part being movable to an operative position in which said arm closes the outer end 75 of said passage and to an inoperative position in which said arm is away from said passage. 80

2. A hollow spark plug body member having a passage therein extending from the exterior to the interior thereof and having an exterior, annular groove, in combination with a spring clip embracing said member within 90 said groove and circumferentially adjustable 95 therein and provided with a yieldable arm projecting therefrom and adapted to engage said member, said clip being movable to an operative position in which said arm closes the outer end of said passage and to an inoperative position in which said arm is away from said passage. 100

3. A hollow spark plug body member having a passage therein extending from the exterior to the interior thereof and having an exterior, annular groove, in combination with a spring clip embracing said member within 105 said groove and circumferentially adjustable therein and provided with a yieldable arm projecting therefrom and adapted to engage said member, said clip being movable to an operative position in which said arm closes the outer end of said passage and to an inoperative position in which said arm is away from said passage, and said arm having a 110 protuberance thereon which enters said passage when said clip is moved to the operative position. 115

In testimony whereof, I affix my signature.

JOHN H. HYDE.
